UNITED STATES PATENT OFFICE

EDWIN E. RIPPSTEIN, OF ST. LOUIS, MISSOURI, ASSIGNEE TO LACLEDE STEEL COMPANY, OF ST. LOUIS, MISSOURI, A CORPORATION OF MISSOURI

REENFORCING UNIT FOR CONCRETE BEAMS

Application filed May 27, 1929. Serial No. 366,190.

This invention relates to reenforcing units of the type comprising a plurality of stirrups or similar elements adapted for arrangement in concrete beams or like structures, and an important object of the invention is to produce reenforcing units of the type referred to which are provided with improved means for anchoring the stirrups of the reenforcing units in place in the upper portion of the concrete structures.

Another object of the invention is to provide a reenforcing unit of the type referred to above with an improved arrangement for maintaining the spacing of the stirrups forming parts of said reenforcing unit.

Another object of the invention is to provide a reenforcing unit of the type to which this invention relates with means constituting a part thereof for supporting reenforcing bars arranged near the top surface of the concrete and extended in a direction transverse with respect to the reenforcing unit.

Still another important object of the invention is to so construct a reenforcing unit of the type to which the invention pertains that the same elements serve the triple function in unit structure of providing (a) the improved anchoring means referred to, (b) the improved spacing means referred to, and (c) the supports mentioned above for supporting the transversely arranged reenforcing bars.

Fig. 1 is a fragmentary perspective view of my improved reenforcing unit.

Fig. 2 is an enlarged cross-section of my improved reenforcing unit showing same as it will appear when in place in a form.

Fig. 3 is an enlarged section on line 3—3 of Fig. 2.

In the drawing, wherein is shown for the purpose of illustration, merely, one embodiment of the invention, A designates my improved reenforcing unit generally, said unit comprising a plurality of stirrups 1 which are spaced longitudinally of the unit, as shown in Fig. 1. The stirrups 1 are each substantially U-shaped in form and are arranged with the open portion thereof at the top of the unit, said stirrups being ar-

ranged in spaced relation longitudinally of the unit, as shown in Fig. 1. To maintain the spaced relationship of the stirrups 1 of a unit, I provide a pair of bars 2 which are extended longitudinally of the unit, said bars being arranged at, or immediately adjacent to, the upper ends of the upright legs of the stirrups, and said longitudinal spacing bars being rigidly secured to said upright legs, preferably by being welded thereto. The spacing bars 2 extend continuously from end to end of the unit structure, and in addition to serving as spacing elements act as anchoring means for anchoring the stirrups in the concrete, and as elements for supporting reenforcing bars arranged transversely of the unit at a point adjacent to the top surface of the concrete.

Associated with certain of the stirrups 1 are supporting elements 3 providing chairs for the unit. Each of the stirrups which has supporting elements associated therewith is provided with a pair of said supporting elements, which are located at opposite sides of the stirrup. The supporting elements 3 preferably comprise members which are semicircular in cross-section, the upper portions of which embrace the lower portions of the upright legs of the stirrups with which they are associated, and said supporting elements 3 are rigidly secured to said upright legs, preferably by being welded thereto.

In Fig. 2 I illustrate the manner in which my improved reenforcing unit is arranged within a form, wherein B designates the form, which is constructed in the usual manner. The unit is arranged within the form B so that the supporting elements 3 rest upon the bottom member of the form and with the unit in its proper spaced relationship with respect to the side walls of the form. The reenforcing bars 4, which constitute parts of the reenforcing system of the concrete structure, are arranged in place in the form, said bars 4 being extended transversely of the unit A and being supported by the longitudinal spacing bars 2 of the unit. Also, reenforcing bars 5 rest upon the lower horizontal members of the U-

100

shaped stirrups, said reenforcing bars being spaced transversely of said horizontal members and being extended longitudinally of the unit A.

5 With the unit and the associated reenforcing bars 4 positioned as described, the concrete is poured into the form B in the usual manner, and because of the weight of the unit itself, and also because of the additional weight of the bars 4 and 5, said unit 10 will be prevented from shifting its position while the operation of pouring the concrete is being performed.

15 The presence of the longitudinal spacing bars 2 at the upper ends of the upright legs of the stirrups 1 of the unit provides cross-like portions at the upper ends of each stirrup, and these cross-like portions serve as anchoring means which very securely anchor the unit within the concrete of the structure 20 being reenforced. Such anchorage heretofore has been provided by means of semi-circular hooks or similar bends at the upper ends of the upright members of the U-shaped stirrups. The longitudinal spacing bars will 25 either eliminate the need of such hooks or bends, or, when used in conjunction with hooks or bends, provide an anchorage of greater strength than has been provided by any means previously employed for the purpose. Also, as already stated, the longitudinal bars serve to space the stirrups and to 30 support the reinforcing bars 4, hence these elements are caused to perform a triple function in the unit structure, whereby said unit structure is very greatly simplified.

33 I claim:

1. A structural unit comprising a plurality of substantially U-shaped stirrups spaced 40 longitudinally of the structural unit, and bars extended longitudinally of the unit at points immediately adjacent to the upper ends of said U-shaped stirrups, said longitudinally extended bars being fixedly secured to said stirrups, and the side members of 45 said U-shaped stirrups being straight from end to end thereof whereby the unit is dependent on the longitudinally extended bars for anchorage.

50 2. A structural unit comprising a plurality of substantially U-shaped stirrups spaced longitudinally of the structural unit, and bars extended longitudinally of the unit at points immediately adjacent to the upper ends of said U-shaped stirrups, said longitudinally extended bars being fixedly secured to said stirrups, and being continuous from end to end of the structural unit, and the side members of said U-shaped stirrups being straight from end to end thereof whereby the unit is dependent on the longitudinally extended bars for anchorage.

55 3. A structural unit comprising a plurality of substantially U-shaped stirrups spaced longitudinally of the structural unit, and

bars extended longitudinally of the unit at points immediately adjacent to the upper ends of said U-shaped stirrups, said longitudinally extended bars being fixedly secured to said stirrups, and being continuous from 70 end to end of the structural unit, and the side members of said U-shaped stirrups being straight from end to end thereof whereby the unit is dependent on the longitudinally extended bars for anchorage, said longitudinal bars being arranged to serve the functions of maintaining the spaced relationship of the stirrups and anchor the unit 75 in the concrete.

4. A structural unit comprising a plurality of substantially U-shaped stirrups spaced longitudinally of the structural unit, and bars extended longitudinally of the unit at points immediately adjacent to the upper ends of said U-shaped stirrups, said longitudinally extended bars being fixedly secured to said stirrups, and being continuous from 80 end to end of the structural unit, and the side members of said U-shaped stirrups being straight from end to end thereof whereby the unit is dependent on the longitudinally extended bars for anchorage, said longitudinal bars being arranged to serve the functions of maintaining the spaced relationship of the stirrup, anchor the unit in 85 the concrete, and support reinforcing bars 90 located above the unit.

5. A structural unit comprising a plurality of substantially U-shaped stirrups spaced 95 longitudinally of the structural unit, bars extended longitudinally of the unit at points immediately adjacent to the upper ends of said U-shaped stirrups, said longitudinally extended bars being fixedly secured to said stirrups, and being continuous from 100 end to end of the structural unit, and the side members of said U-shaped stirrups being straight from end to end thereof whereby the unit is dependent on the longitudinally extended bars for anchorage, said longitudinal bars 105 being arranged to serve the functions of maintaining the spaced relationship of the stirrup, anchor the unit in the concrete, and support reinforcing bars located above the 110 unit, and elements for supporting the structural unit.

115 In testimony that I claim the foregoing I hereunto affix my signature.

EDWIN E. RIPPSTEIN.
